SHIPPING AND DISPLAY CARTON

Carl G. Fulmer, Chicago, and Daniel Int-Hout,
Park Ridge, Ill., assignors to Lever Brothers
Company, a corporation of Maine

Application July 29, 1948, Serial No. 41,203

2 Claims. (Cl. 206—45.11)

1

This invention is directed to a shipping and display carton for elongated articles. The principal object of this invention is to provide a shipping and display carton wherein elongated articles which may be broken or damaged in shipment, such as glass tooth brush holders, plaster pencils and the like, may be firmly held therein for shipment without breakage or damage, wherein the elongated articles may be securely held during shipment adjacent both ends for protecting them in shipment, wherein the ends of the articles are protected during shipment against breakage or damage, wherein the articles may be attractively displayed for merchandising purposes, wherein the articles are firmly held during display, wherein a portion of the carton may be unfolded for attractively displaying the articles, wherein the carton may be readily provided with advertising and display material, wherein the advertising and display material may not be damaged or marred during a shipment, and wherein the carton may be readily and inexpensively manufactured.

In carrying out this object of the invention the shipping and display carton preferably includes a pair of boxes for receiving the elongated articles and which may be hinged together at one end so that they may be arranged side by side for shipping purposes and may be unfolded toward an end to end position for display purposes. This provides a compact unit for shipping purposes and a spread unit for display purposes.

Preferably the top surfaces of the boxes are provided with holes for receiving the lower portions of the elongated articles so that the articles are held in proper position and advantageously displayed. The boxes also include a liner having holes for receiving the lower portions of the elongated articles and for engaging and protecting the lower ends thereof. Proper positioning of the lower ends of the articles and protection of the same is thereby afforded.

The shipping and display carton also includes a cover for enclosing the elongated articles and the pair of boxes when folded side by side. The cover is also preferably provided with a liner having holes for receiving the upper portions of the articles and engaging the upper ends of the articles. Thus proper positioning of the upper ends of the articles and protection of the same during

2

shipment is likewise afforded. The cover, used in shipping, not only protects the articles, but also protects the advertising and display material on the boxes.

5 The boxes, cover and liner may be inexpensively and readily manufactured from blanks, such as cardboard and the like, by folding and securing, and the shipping and display carton may be readily and inexpensively assembled during the packing of the articles.

10 Further objects of this invention reside in the details of construction of the shipping and display carton and the cooperative relationship between the component parts thereof.

15 Other objects and advantages will become apparent to those skilled in the art upon reference to the accompanying specification, claims and drawing in which:

Figure 1 is a perspective view partly in section 20 illustrating one form of the shipping and display carton;

Figure 2 is a vertical sectional view taken substantially along the line 2—2 of Figure 1;

Figure 3 is a horizontal sectional view taken 25 substantially along the line 3—3 of Figure 2;

Figure 4 is a plan view of the blank forming the cover;

Figure 5 is a plan view of the blank forming the boxes;

Figure 6 is a plan view of the blank forming the liner for the cover;

Figure 7 is a plan view of the blank forming the liners for the boxes;

Figure 8 is a perspective view partly in section 35 similar to Figure 1, but illustrating another form of the invention;

Figure 9 is a sectional view taken substantially along the line 9—9 of Figure 8;

Figure 10 is a plan view of the blank of the liner for the cover utilized in Figure 8;

40 Figures 11 and 12 are plan views of the liners for the boxes utilized in the form of the invention illustrated in Figure 8;

Figure 13 is a view similar to Figure 1, but illustrating another form of the invention;

Figure 14 is a sectional view taken substantially along the line 14—14 of Figure 13;

Figure 15 is a plan view of the blank forming the liner for the cover of the form of the invention illustrated in Figure 13;

Figure 16 is a perspective view illustrating the boxes containing the articles spread for display purposes.

Referring first to the form of the invention illustrated in Figures 1 to 7, the shipping and display carton is generally designated at 10. It includes a pair of boxes 11 and 12 which are preferably hinged together at one end so that they may be arranged side by side for shipping purposes as illustrated in Figure 1, or may be spread toward an end to end position for display purposes as illustrated in Figure 16. The top surfaces of the boxes 11 and 12 are provided with holes 13 for receiving the lower ends of elongated articles 14 such as glass tooth brush holders. The boxes 11 and 12 contain liners 15 and 16 respectively, the liners having holes 17 in the top surface thereof for also receiving the lower portions of the elongated articles. The liners are provided with an intermediate surface upon which the lower ends of the articles rest and by which the lower ends of the articles are spaced from the bottom of the boxes. The holes 13 and 17 in the boxes and the liners therefore operate to hold the lower portions of the elongated articles 14 in a vertical position and the liners, also, operate to space the lower ends of the articles from the bottom of the boxes. Thus, the articles are firmly held for display purposes and for shipping purposes in the boxes 11 and 12.

A cover 18 is adapted to enclose the articles 14 and the boxes 11 and 12, and is utilized for shipping purposes. The cover 18 is provided with a liner 19 having holes 20 for receiving the upper portions of the elongated articles 14 for securely holding them during shipping. The liner 19 is, also, provided with a surface which is spaced from the top of the cover 18 and which is engaged by the upper ends of the articles 14 whereby the articles are held spaced from the top of the cover 18 and damage to the ends of the articles is therefore prevented during shipping.

During shipping, the cover 18, the boxes 11 and 12, and the liners 15 and 16 and 19 operate to firmly hold the articles 14 and prevent breakage thereof or damage thereto. The cover 18, in addition, operates to protect any advertising or display material which is placed on the boxes 11 and 12. When the articles are to be displayed the cover 18 and liner 19 are removed whereupon the articles 14 are vertically held by the boxes 11 and 12 and the liners 15 and 16 therein. To add to the attractiveness of the display the boxes 11 and 12 may be spread about the hinge joint, as is illustrated in Figure 16 and the boxes 11 and 12 may be provided with suitable advertising for display material. The shipping and display carton thereby provides a compact unit for shipping purposes, but yet allows a spread unit for display purposes.

The boxes 11 and 12 may be formed from a blank of material such as cardboard and the blank for the boxes is illustrated in Figure 5. The body portion of the blank 11 is scored to provide a bottom surface 22, a side surface 23, a top surface 24 including the holes 13, a side surface 25 and a securing flap 26. The securing flap 26 is suitably secured as by adhesive to the bottom surface 22 to form a box like structure. The blank is also provided with flaps 27, 28, 29, 30 and 31 which are adapted to be folded over to form the boxes 11 and 12. In this respect both boxes 11 and 12 are identical.

One of the boxes such as the box 12 is provided at one end with an additional flap 34 which is 75

adapted to be received in the corresponding end of the other box 11 as is illustrated in Figure 3. This flap 34 may be frictionally received in the end of the box 11 or it may be adhesively secured therein. In any event the flap 34 provides a hinge between the two boxes 11 and 12 so that the boxes may be arranged side by side as illustrated in Figure 1 for shipping purposes or may be extended toward an end to end position as illustrated in Figure 16 for display purposes.

The blank for the liners 15 and 16 for the boxes 11 and 12 is illustrated in Figure 7. The blank is scored to form a top surface 36, a side surface 37, an intermediate surface 38 and a side surface 39, and also, a side surface 40, a bottom surface 41 and a side surface 42. The side surface 39 is adhesively secured to the side surface 40 and the side surface 37 is adhesively secured to the side surface 42 as illustrated in Figure 2. The liner thus formed provides a top surface 36 having the holes 17 for receiving the lower portions of the articles 14, an intermediate surface 38 engaged by the lower ends of the articles 14 and a bottom surface 41 engaging the bottom surface 22 of the boxes 11 and 12.

The blank for forming the cover 18 is illustrated in Figure 4 and it is scored to include a securing flap 44, a front surface 45, a side surface 46, a back surface 47, and a side surface 48. The flap 44 is secured to the surface 48 to form a box like construction. The blank also includes flaps 49, 50 and 51 which are folded to close the top of the cover. The cover is adapted to enclose the articles 14 and the boxes 11 and 12. To facilitate removal of the cover, the front and back surfaces thereof are provided with cutouts 52 so that the boxes 11 and 12 may readily be grasped during the removal of the cover 18.

The blank for forming the insert 19 for the cover 18 is illustrated in Figure 6. It is scored to include a securing flap 54, a surface 55 to be engaged by the upper ends of the articles 14, a side surface 56, a bottom surface 57 including the holes 20 for receiving the upper portions of the articles 14 and a side surface 58. The securing flap 54 is secured to the side surface 58 to form a box like structure. The ends of the surface 55 are provided with flaps 59 and 60 which are adapted to be folded upwardly for the purpose of spacing the surface 55 from the top of the box 18. The surface 55 is also cut to form ears 61 and 62 which extend upwardly during the folding operation. These ears also operate to space the surface 55 from the top of the cover 18. The liner 19 in the cover 18 therefore operates firmly to hold the upper portions of the articles 14 and to maintain the upper ends of the articles 14 spaced from the top of the cover. In this way breakage and damage to the articles 14 is prevented during shipping.

Referring now to the form of the invention illustrated in Figures 8 to 12 it includes the same boxes 11 and 12 and the same cover 18 as in the previous form of the invention and therefore like reference characters have been utilized for like parts. The form of the invention illustrated in Figures 8 to 12 differs from that of Figures 1 to 7 in the specific construction of the liners for the boxes 11 and 12 and the liner for the cover 18. The liners for the boxes 11 and 12 are designated at 71, 72, and at 73, 74 respectively, and the liner for the cover is designated at 75.

The liners of the boxes 11 and 12 are made

in two parts instead of one part as in the previous form of the invention. The blank for forming one of the liners 71 is illustrated in Figure 11 and the blank for forming the other liner 72 is illustrated in Figure 12. The blank for forming the liner 71 is scored to provide a securing flap 77, a bottom surface 78, a side surface 79, a top surface 80 having the holes 17 and a side surface 81. The securing flap 77 is suitably secured to the side surface 81 to form a box like structure.

The blank for forming the liner 72 is scored to provide a securing flap 82, a bottom surface 83, a side surface 84, a top surface 85 and a side surface 86. The securing flap 82 is suitably secured to the side surface 86 to provide a box like structure. The liner 72 is first placed in the box 11 or 12 with the bottom surface thereof engaging the bottom surface of the box and then the other liner 71 is inserted with the bottom surface thereof engaging the top surface of the liner 72. The function of the liners 71 and 72 is the same as the function of the liner 15 of the previous form of the invention.

The blank for forming the liner 75 for the cover 18 is illustrated in Figure 10. It is scored to provide a securing flap 88, a top surface 89, a side surface 90, a bottom surface 91 having the holes 20 for receiving the upper portions of the articles 14 and an oversized side surface 92. The securing flap 88 is secured to the side surface 92 to form a box like structure and the side surface 92 extends upwardly above the top surface 91 for the purpose of spacing the top surface 91 from the top of the box 18. The ends of the top surface 89 are provided with flaps 93 and 94 which are also folded upwardly for the purpose of spacing the top surface 89 from the top of the box 18. The top surface 89 is also cut to form an ear 95 which extends upwardly also to space the top surface 89 from the top of the box 18. The function and operation of the liner 75 is the same as the liner 19 of the previous form of the invention.

The forms of the invention illustrated in Figures 1 to 12 are shown for the purpose of receiving elongated articles such as glass receptacles for tooth brushes. The form of the invention illustrated in Figures 13 to 15 is illustrated for accommodating other elongated articles such as plaster pencils. However, it should be obvious that any type of elongated article may be suitably accommodated by any of the forms of the invention. Essentially the form of the invention illustrated in Figures 13 to 15 embodies the same elements as the previous forms of the invention. The construction of the boxes 11 and 12 is the same as that previously described, the dimensions are somewhat changed and circular holes 101 are utilized in lieu of holes 13 in order to accommodate the cylindrical elongated articles 102 such as plastic pencils. The liners for the boxes are the same as the liners 71, 72, 73 and 74 with the exception as to dimensions and the provision of round holes 103 for accommodating articles 102. The cover 18 is the same in all forms of the invention. The liner 104 differs somewhat from the liners for the covers previously described. In this respect the liner 104 is provided with circular holes 105 for receiving the upper ends of the elongated articles 102 and is scored to form a securing flap 107, a top surface 108, a side surface 109, a bottom surface 110 and a side surface 111. The securing flap 107 is secured to the side surface 111 to provide a box

like structure. The top surface 108 is cut to provide ears 112 and 113 which extend upwardly for the purpose of spacing the top surface 108 from the top of the cover 18. The basic difference between the liner 104 therefor and the liner 19 of Figure 6 is that the ears 59 and 60 of the latter are omitted.

The boxes, covers and liners while differing in specific respects in the various forms of the invention all operate, however, in the same manner for obtaining the same results. Namely, to provide a shipping and display carton for shipping elongated articles without breakage or damaging the same and for attractively displaying the articles.

While for purposes of illustration several forms of this invention have been disclosed, other forms thereof may become apparent to those skilled in the art, and therefore, this invention is to be limited only by the scope of the appended claims.

We claim as our invention:

1. A shipping and display carton for elongated articles comprising a pair of boxes, one of said boxes having a flap at one end which is received in one end of said other box to hinge said pair of boxes together at one end which are adaptable to be moved in a side by side shipping position and an end to end display position, said boxes having holes in the top surface thereof for receiving the lower portions of the elongated articles with the upper portions thereof protruding upwardly from the boxes, a liner in each box having a surface spaced from the top surface of the box provided with holes for also receiving the lower portions of the elongated articles, a cover of greater depth than the height of the pair of boxes for enclosing the upwardly protruding elongated articles and the pair of boxes when arranged side by side, and a liner in the cover having a surface spaced from the top surface of the cover for engagement by the upper ends of the upwardly protruding elongated articles, the holes in said boxes and in all of said liners being in substantial alignment.

2. A shipping and display carton for elongated articles comprising a pair of boxes, one of said boxes having a flap at one end which is received in one end of said other box to hinge said pair of boxes together at one end which are adaptable to be moved in a side by side shipping position and an end to end display position, said boxes having holes in the top surface thereof for receiving the lower portions of the elongated articles with the upper portions thereof protruding upwardly from the boxes, a liner in each box having a surface spaced from the top surface of the box provided with holes for also receiving the lower portions of the elongated articles and having another surface spaced from the bottom surface of the box for engagement by the lower ends of the elongated articles, a cover of greater depth than the height of the pair of boxes for enclosing the upwardly protruding elongated articles and the pair of boxes when arranged side by side, and a liner in the cover having a surface spaced from the top surface of the cover provided with holes for receiving the upper portions of the upwardly protruding elongated articles and another surface spaced from the top surface of the cover for engagement by the upper ends of the upwardly protruding elongated articles, the holes in said

boxes and in said first- and second-mentioned liners being in substantial alignment.

CARL G. FULMER.
DANIEL INT-HOUT.
